UNITED STATES PATENT OFFICE.

CHARLES S. CUSHMAN, OF BARRE, VERMONT.

STONE POLISHER.

Application filed June 2, 1925. Serial No. 34,459.

This invention relates to new and useful improvements in stone polishing devices, and particularly to rotary polishing devices.

The present application embodies improvements on my prior Patent 1,491,790, issued April 29, 1924, and my pending application Serial Number 737,116.

One improvement resides in the provision of novel means for moving the polishing element longitudinally of the surface of the stone being polished, whereby to produce a continuous movement thereof.

Another improvement resides in the provision of novel means for causing the polishing element to travel in an orbital direction as well as in an axial direction, whereby to cover a large portion of the surface of the stone, during the movement of the polishing element lengthwise of the stone.

Another object is to provide means whereby the axial movement and the orbital movement are correlated to provide for the governing of one by the other.

Other objects and advantages will be apparent from the following description when taken in connection with the accompanying drawings.

In the drawings:

Figure 1 is an elevation of the device in operative position with relation to a stone to be polished.

Figure 2 is an elevation looking toward the left side of Figure 1, partly broken away.

Figure 3 is a top plan view of the same.

Referring particularly to the accompanying drawing, 10 and 11 represents a pair of parallel I-beams, properly supported and held in spaced relation. Disposed beneath these beams 10 and 11 is a carriage 13, which is supported from the lower flanges of said beams by the wheels 12. Extending upwardly from the carriage is an arm 15, on which are mounted the trolley wheels 13', and which engage with the trolley wires 14, which are supported in parallel relation to, and adjacent one of the said beams. On the carriage 13 is mounted an electric motor 16, the shaft 17 of which is provided with a gear 18 meshing with a gear 19, on a counter-shaft 20, arranged adjacent thereto. On the other end of the counter-shaft 20 is formed a worm 21 which meshes with a worm wheel 22 carried by the upper portion of the vertical shaft 23, which is mounted on the carriage, at 14. On the shaft 23, above

the worm wheel 22, are mounted the winding drums 24 and 25, and connected to these drums, and wound thereon in opposite directions, are the cables 26 and 27, the other ends of the cables being suitably anchored, or secured adjacent the ends of the beams 10 and 11. Swiveled on the lower end of the shaft 23, below the carriage, is an L-shaped member 28, and carried by the horizontal arm of said member is a horizontally extending arm 29, provided with a terminal stop collar 30. Engaged on this arm, for sliding movement longitudinally thereof, is a strap 31, which is connected with the horizontal bar 32. Connected to, and depending from the ends of these bars 32 are the cables 33, the lower ends of which are connected to the ends of similar bar 34, whose intermediate portions are swivelly connected to the upper end of the lug 35, of the casing of the motor 36, of the stone polishing element 37. Connected to and extending between the cables 33, are the spacing bars 38, which serve to prevent twisting and tangling of the cables, during the operation of the machine.

On the vertical shaft 23, between the lower and of the carriage 13, and the member 28, are the collector rings 39, which are engaged by the brushes 40, carried by the said member 28, and through the medium of which electric current is conveyed to the motor 36, of the stone polishing element 37, electric conduits 41 being provided for conveying current from the trolley wheels 13' to the collector rings 39, and other conduits 42 being provided for conveying current from the trolley wheels to the motor 16.

Upon starting the motor 36, the polishing element 37 will be rotated on the surface of the stone, in an axial direction, whereupon the bars 34 will be swung around with the result that a twisting movement will be imparted to the cables 33, and transmitted to the upper bars 32, to exert a turning movement to the vertical shaft 23. This turning movement, however, will be resisted and prevented by the worm gear and worm. Upon current being applied to the motor 16, the shaft 23 will be rotated to cause the arm 29 to rotate about the shaft as its axis, with the result that the polishing element will be turned in an orbital direction, on the surface of the stone. Thus the polishing element turns about its axis, and at the same time turns in an orbital path, which is cir-

cular, with the result that the polishing element will travel circularly and transversely of the surface of the stone. Before starting the machine, the cable 26 is secured at its outer end to a stationary element, not shown, whereby, as the motor 16 rotates this cable will be wound on the drum to draw the carriage, and the parts connected therewith, longitudinally of the stone to be polished, the other cable being loose. When the polishing element has reached the end of the stone, the cable 26 is loosened, and the cable 27 secured to a stationary element, whereupon the said cable 27 will be wound on its drum, and the carriage, and associated parts drawn to the other end of the stone.

Thus the polishing element is driven transversely and longitudinally of the stone's surface, and at the same time describes a circular axial, and a circular orbital movement thereon, with the result that the entire surface of the stone will be properly and evenly treated, without the manual operation of the attendant, who simply controls the switches, and the cable ends.

If desired, the motor 16 may be driven in a direction opposite to that in which the polishing element impels the shaft 23, by reversing the electric current which flows to the said motor.

What is claimed is:

1. A polishing device comprising, in combination with an elevated support, of a motor driven polishing element, means between the support and said polishing element adapted to suspend the latter while operable to permit the weight of the element to rest upon a surface to be polished, said suspending means being adapted to twist upon reaction of the motor to the resistance resulting from the frictional contact of said element with the surface to be polished, whereby to tend to elevate said element into proper polishing contactual pressure against said surface, and means associated with the suspending means for driving the polishing element in an orbital direction.

2. A polishing device comprising the combination with an elevated support, of a motor driven polishing element, a flexible twistable suspending means between the support and the motor driven element, said flexible element being adapted to be twisted by the motor of the element due to the resistance offered by the surface to be polished to the

polishing element, whereby said element will be raised from the surface to be polished to a sufficient degree to reduce the frictional contact between the surface and said element and said element permitted to rotate, and means associated with the suspending means for turning the polishing element orbitally.

3. A polishing device comprising the combination with an elevated track, of a motor driven polishing element, a flexible suspending means between the track and element whereby said element is capable of movement to be positioned with reference to the surface to be polished, said flexible suspending means being adapted to be twisted by the motor of the motor driven element due to the resistance offered by the surface to be polished to the polishing element, whereby said element will be raised from said surface to a sufficient degree to reduce the frictional contact between said surface and said element and said element permitted to rotate on said surface, and independently driven means connected with the suspending means for driving the element orbitally on the surface to be polished.

4. A polishing device comprising the combination with an elevated support, of a polishing element including a driving motor, and flexible means supporting the polishing element from the elevated support and operable by the reaction of the motor to the resistance to the rotation of the polishing element offered by the surface to be polished whereby to lessen the pressure between the polishing element and the surface to be polished, means associated with the flexible means for moving the polishing element longitudinally of the surface to be polished, and means associated with the flexible means for driving the polishing element orbitally.

5. In a polishing device, a rotatable polishing element normally resting with its full weight on the surface to be polished, means for rotating said element, and flexible suspending means for said element arranged to be twisted by said driving means when the latter is initially set in motion whereby to tend to elevate the element to a degree sufficient to produce the proper polishing contactual relation between the element and the surface to be polished, and means actuated by the rotating means for moving the polishing element orbitally on the surface.

In testimony whereof, I affix my signature.

CHARLES S. CUSHMAN.
